HOOK-INSERTING TOOL

Louis Simonin, Hillsboro, Ill.

Application January 17, 1946, Serial No. 641,816

3 Claims. (Cl. 145—50)

1

The invention relates generally to tools used by linemen, and more particularly to a tool to assist a telephone lineman in installing a hook to support an insulator.

The general object of the invention is to provide a novel tool facilitating the installation of insulator hooks, which is adapted to be used with other tools ordinarily carried by a telephone lineman, and which permits them to install the hooks quickly and with a minimum of effort.

Another object is to provide a novel tool of the foregoing character, which may be easily placed on a hook and removed therefrom, and which engages the hook without marring the threads thereon.

A further object is to provide a novel tool of the foregoing character, which so interfits with the hook that, when end pressure is placed on the tool to force the hook inwardly, the tool is held in axial alignment with the hook.

Other objects and advantages will become apparent from the following description taken in connection with the accompanying drawings, in which:

Figure 1 is a perspective view showing the manner in which an insulator hook of the character herein contemplated is installed.

Fig. 2 is an elevational view of an insulator hook with the insulator removed therefrom.

Fig. 3 is an elevational view of a tool for installing a hook of the character shown in Fig. 2, which tool embodies the features of the invention.

Fig. 4 is a fragmentary longitudinal sectional view of the tool shown in Fig. 3 and showing the relation of the tool to the hook.

Fig. 5 is an elevational view of the tool and taken in a plane at a right angle to the plane of Fig. 3.

In installing a telephone in a building such as a house, the wire which extends from a nearby pole is secured to an insulator usually mounted on the side of the house. The insulator is so secured to the structure of the house that it will carry the physical stress of supporting the wire. Thus, in Fig. 1, I have shown a portion of a house at 10 with an insulator 11 mounted thereon. The insulator is usually made of ceramic material or the like and preferably has a spool-like form. To support the insulator, a hook, indicated generally at 12, is provided.

The hook 12 is of standard form and comprises a shank 13 provided at its end with wood-screw threads 14 adapted to be screwed into the structure of the building. Intermediate the ends

2

of the hook an offset portion 15 is provided and the outer end of the hook, indicated at 16, is bent at an angle to the shank to extend upwardly and outwardly from the building structure to receive the insulator 11. The end portion 16 is threaded as at 17 to receive a nut 18 adapted to hold the insulator 11 on the hook. It is common practice among telephone linemen to install such a hook by first driving a starting hole in

the building structure into which the threaded end 14 of the hook is inserted. Such starting hole is frequently formed merely by driving a spike a short distance into the building structure and then removing it.

In screwing the hook into the building after inserting it into the starting hole, considerable torque is required, and the lineman has difficulty in applying such torque if he merely attempts to do so by means of pliers or an ordinary wrench. However, a telephone lineman usually carries, as part of his kit, a carpenter's brace, so that if a tool adapted to be utilized with such a brace were provided, the insertion of the hook would be greatly facilitated. The present invention provides such a tool.

As shown in the drawings, the preferred embodiment of the tool comprises a shank 20 provided at one end with a tapering squared portion 21 of usual form to fit into a carpenter's brace. On the other end of the shank 20 there is provided means for gripping the hook and holding it in accurate axial alignment with the brace. To this end, such means comprises a pair of jaws 22 spaced apart sufficiently to embrace the hook 23 and preferably of sufficient width and length, as indicated in Fig. 4, to completely embrace the offset portion 15 of the hook. Extending generally laterally from the jaws and in proper angular relation is a tubular extension 23 adapted to receive the portion 16 of the hook. The tubular extension 23 is of substantial length and extends for a substantial distance laterally from the jaws so that adequate torque may be applied to the hook without chance of damaging the threads 17 thereon. The bore of the tubular extension 23 extends through the space between the jaws 22 so that the tool may be placed on the hook merely by sliding it laterally over the end portion 16 thereof.

As heretofore mentioned, some end pressure must be applied to the hook by the tool when inserting it into the starting hole in the building structure. Such end pressure is necessary in order to cause the threads 14 to bite into the

wood of the building. The particular angular relationship of the portion 16 of the hook to the shank 12 would tend to cause the tool to shift laterally on the hook, when end pressure is applied, and thus would tend to cause the tool to become misaligned with the hook. To prevent such action from occurring, I so form the tubular extension 23 as to engage the offset portion 15 of the hook when the shank 20 of the tool and the shank 12 of the hook are aligned. Thus, the tubular extension 23 has a portion 24 extending between the jaws 22 to engage the bend of the offset portion 15 when the shank 20 of the tool and the shank 12 of the hook are in axial alignment. Consequently, when end pressure is applied to the tool, it will tend to shift laterally, because of the angular position of the tubular extension 23, until the portion 24 engages the offset portion 15, and at such time proper alignment of the tool and hook are provided.

From the foregoing description, it will be apparent that I have provided a novel tool to facilitate the work by a telephone lineman of installing an insulator hook. With a tool of the character herein disclosed, such hooks may be quickly installed with a minimum of effort. The tool is easily placed on and removed from the hook and engages it in such a manner that the threads thereon will not become marred and so that torque may readily be applied to the hook to screw it into the building structure. The tool interferes with the hook in such a way that, when end pressure is applied to the tool, it shifts to an aligned position with the hook.

I claim:

1. A tool for inserting a hook formed with a shank portion, a stem portion extending at an obtuse angle to said shank portion and a bent offset portion between said shank and stem portions, the bend of said offset portion lying in the plane passing through the shank and stem portions, said tool comprising a shank, a pair of parallel spaced jaws extending from the end of the shank, the spacing of said jaws being sufficient to embrace the offset portion of said hook, and a tubular extension projecting generally laterally from the jaws and at substantially the same angle to the jaws as that between the shank and stem portions of the hook and adapted to receive the stem of the hook, said tubular extension having a portion projecting between the jaws to engage in the bend of the offset portion of the hook, whereby the shank of the hook and the shank of the tool become axially aligned upon application

of end pressure to the shank of the tool and toward the hook.

2. A tool for inserting a hook having a shank portion, a stem portion extending at an obtuse angle to said shank portion and a bent portion connecting said shank and stem portions, said bent portion lying in the plane of said shank and stem portions, comprising a shank, a pair of spaced jaws extending from the end of the shank and adapted to embrace the bent portion of the hook, and a tubular extension projecting laterally from the jaws at substantially the same angle to the jaws as that between the shank and stem portions of the hook, the space between the jaws adjacent the tubular extension forming a continuation of the bore of said extension whereby the tool may be readily placed on the hook by sliding it laterally over the stem of the hook, the angular relation of the tubular extension to the jaws causing the bent portion of the hook to shift into engagement with the inner end of the tubular portion when end pressure toward the hook is applied to the shank of the tool.

3. A tool for inserting a hook comprising a threaded shank portion, a stem portion extending at an obtuse angle to said shank portion, and a bent portion lying in the plane defined by said shank and stem portions, said tool comprising a shank, a pair of spaced jaws extending from one end of the shank of the tool and adapted to embrace said bent portion of the hook, and a tubular extension projecting laterally at said end of the shank of the tool at the same angle to the jaws as that between the shank and stem portions of the hook to receive the stem portion of the hook, said tubular extension having a portion extending between the jaws to engage in said bent portion and thereby prevent the tool from shifting laterally of the hook when end pressure toward the hook is applied to the shank of the tool, said end pressure forcing the shank portion of the hook into centered relation with said shank of the tool by virtue of the angular relation between said extension and the shank of the tool.
